UNITED STATES PATENT OFFICE.

HARRY V. HAIGHT, OF SHERBROOKE, QUEBEC, CANADA, ASSIGNOR TO INGERSOLL-RAND COMPANY, OF JERSEY CITY, NEW JERSEY, A CORPORATION OF NEW JERSEY.

PNEUMATICALLY-CONTROLLED RHEOSTAT.

Application filed August 17, 1926. Serial No. 129,804.

This invention relates to rheostats and with respect to its more specific features to pneumatically operated apparatus for controlling said rheostats.

5 An object of the invention is to enable a rheostat, more particularly a liquid rheostat, to be operated pneumatically and to be controlled so as to provide any desired degree of resistance. Another object of the invention is to enable the operator to adjust the rheostat to any predetermined amount of resistance. Other objects and advantages of the invention will be in part obvious and in part pointed out hereinafter.

15 In the drawings forming a part of the specification, and in which similar reference characters refer to similar parts.

Figure 1 is a side elevation partly in section showing a liquid rheostat and pneumatically controlled apparatus therefor constructed in accordance with the practice of the invention;

20 Figure 2 is a vertical section of the follow-up valve taken along the line 2—2 of Figure 4 looking in the direction of the arrows;

Figure 3 is a horizontal section of the locking apparatus taken along the line 3—3 of Figure 1 looking in direction of the arrows;

25 Figure 4 is a broken vertical end view of the rheostat and pneumatic controlling apparatus;

Figure 5 is a horizontal section taken 30 along the line 5—5 of Figure 1 looking in the direction of the arrows;

Figure 6 is a vertical section through the switch control valves taken along the lines 40 6—6 of Figure 4 looking in the direction of the arrows; and

Figure 7 is a vertical section through one of the safety switch control valves taken along the lines 7—7 of Figure 4 looking in the direction of the arrows.

45 Referring to the drawings, the rheostat comprises a tank A supported on suitable legs B. Within the tank A is located a stationary electrode D which may be formed integral with the base of the tank, with 50 which are adapted to co-operate a plurality of movable electrodes E. The number of the electrodes E depends upon the character of the electric current. In this instance there are three electrodes E, the current being three-phase and the leads K adapted

to be connected at the rheostat in a Y arrangement. The movable electrodes E are suspended by rods F from a spider G, which is adapted to be guided in its vertical movement on a hollow tube H extending vertically within the tank A. The rods F are provided with suitable bushings J of insulating material to prevent short circuiting of the leads K attached to the rods F. Preferably the leads K are flexible and clamped at the upper end of the tube H by means of clamps L. If desired, the leads K may pass from the tank through the tube H to the motor or other suitable apparatus to which they are to convey current. The electrodes E may be of any suitable form; in this instance they consist of heavy plates O formed integrally with a spider P attached to the lower ends of the rods F. A split cylindrical shell Q attached to the plates O and extending upwardly therefrom provides a large surface to contact with a suitable fluid R providing the resistance between the stationary electrodes D and the movable electrodes E. The fluid is preferably cooled by a spirally disposed pipe S submerged in the fluid R and supplied with cooling water through a pipe connection T extending through the bottom of the tank A. The tube H is braced from the inside of the tank by suitable rods U extending from the inside of the tank to the tube H. A conical cover V is provided to prevent foreign matter from entering the tank A.

55 In order to control the resistance provided by the rheostat, a lever W pivoted preferably outside the tank is attached by a pin X to the spider G, by means of which the electrodes E are lifted or lowered as desired. A counter-balancing weight Y is provided at the end of the lever W to facilitate the raising of the spider G and the parts attached thereto. Raising and lowering of the spider G is effected by a pneumatically operated piston Z adapted to reciprocate in a cylinder b suitably mounted on a base c attached to one of the legs B of the tank A. The piston Z may be of any desired construction, in this instance being provided with a cup leather d held in place by a plate e bolted to the lower face of the piston. The upper end of the piston Z is provided with a tube f extending from the piston through the cylinder head g having a gland h and

suitable packing material *j*. The piston rod *k* is attached at a ball and socket joint *o* to the piston *Z* and extends through the tube *f* to connect with the longer arm *p* of a bell 5 crank attached to a shaft *q* about which the bell crank turns. The shorter arm *r* of the bell crank is connected by a link *s* to the lever *W*.

The piston *Z* is double acting, and motive 10 fluid for its actuation is admitted to the top of the cylinder *b* through a pipe *t* and at the lower end of the cylinder through a pipe *u*. The motive fluid, preferably compressed air, for actuating the piston *Z* is controlled by 15 an apparatus comprising a hand-operated lever *v* attached at one end to a link *w* connected to an operating arm *x* mounted on a shaft *y*. The rotation of the shaft *y* and the gear *z* rigidly mounted thereon causes rotation 20 of a second shaft *2* by means of a pinion *3* keyed or otherwise suitably attached to the shaft *2*. An arm *4* is attached to the shaft *2* and rotates therewith. An outwardly extending arm *5* on the shaft *q* provides a 25 floating pivot *6* for a lever *7* adapted to be raised and lowered by the arm *4* by means of a link *8*. The position of the pivot *6* varies with the position of the lever *W*, and this 30 variable leverage is utilized to control a follow-up valve hereinafter described.

The follow-up valve is shown in detail in Figure 2 and comprises a valve chest *9* having an inner chamber *10* connected by means of a pipe *11* to a port *12*. A pair of valves 35 *13* and *14* controls the supply of motive fluid to the chamber *10* within the valve chest *9* and its exhaust therefrom. The valves *13* and *14* are provided with plungers *15* and *16*, respectively, which are adapted to contact 40 with a cam *17* provided with a pivot *18* and actuated through an arm *19* formed integrally with the cam connected by means of a link *20* to the floating lever *7*. Motive fluid is supplied to the valve chest *9* through a 45 pipe *21* connected at a chamber *22*. The valve *13* controls communication between the chamber *22* and the chamber *10* leading to the pipe *11* and thence to the cylinder *b*. Normally, the valve *13* is held on its seat by 50 means of a compression spring *23* within the valve chamber *10*. The exhaust of motive fluid from the chamber *10* is controlled by the valve *14*, which is adapted to control communication between the chamber *10* and a chamber *24* suitably connected to atmosphere. It will be seen that actuation of the plunger *15* by the cam *17* permits motive 55 fluid to flow from the supply pipe *21* into the chamber *10* and thence to the pipes *t* and *u*, supplying motive fluid to both ends of the cylinder *b* and exposing the upper and lower faces of the differential piston *Z* to pressure. The lower face of the piston *Z* being larger 60 than the upper face, the unbalanced pressure causes the piston *Z* to rise, thereby raising 65

the counterweight *Y* and lowering the spider *G* and its associated electrodes *E*. Depressing the plunger *16* permits the compressed air to escape from the cylinder *b* to atmosphere through the chamber *10* and chamber 70 *24*, whereupon the counterweight *Y* causes the electrodes *E* to separate from the stationary electrode *D*.

The arm *4* is adapted to swing in either direction from its uppermost position to 75 lower the lever *7*. In Fig. 1 the arm *4* is shown swung in a clockwise direction. A similar movement in a counter-clockwise direction will also depress the lever *7* and produce a similar effect on the cam *17*. The 80 movement of the arm *4* is effected as has been above described by the longitudinal movement of the link *w*. It is intended that a vertical position of the lever *v* shall be the neutral position at which the electrodes *E* are 85 raised from the surface of the liquid *R* in the tank *A*. The apparatus is arranged to be associated with a double throw switch (not shown), as for instance a pneumatically operated switch of the character shown in co-pending application of Harry V. Haight, Serial No. 39,669, filed June 26, 1925.

Means are provided by this invention to automatically throw the double throw reversing switch to either of its positions upon 90 movement of the lever *v* from its vertical or neutral position. To this end there is provided a pair of valves *30* and *31* (Figs. 6 and 3) controlling the supply of compressed air to a pair of supply pipes *32* and *33* respectively leading to the reversing double throw switch. The valves *30* and *31* are actuated by a cam *34* mounted on the shaft *y* and the flat face *35* of the cam *34* is adapted to lie horizontally, when the arm *4* stands vertically. Movement of the arm *4* in either direction from the vertically is accompanied by an opposite movement of the cam *34* to open one of the valves *30* and *31* and thereupon to admit motive fluid into one or the other of the pipes *32* and *33*, respectively, for actuating the reversing switch.

The valves *30* and *31* are mounted in a casing *36* supported by the main valve casing *9*. The casing *36* is provided with a pair of chambers *37* and *38* connected with the pipes *32* and *33* respectively and controlled by the valves *30* and *31* respectively. A constant pressure chamber *39* into which both the valves *30* and *31* extend is supplied with 115 motive fluid under pressure at all times, which is adapted to be admitted into the chamber *37* from the chamber *38* depending upon which of the valves *30* and *31* is lifted from its seat by the cam *34*. Normally the valves *30* and *31* are held to their seat by 120 means of springs *40* bearing against the heads of the valves and held in place by caps *41* threaded into apertures leading to the chamber *39*. The stems of the valves *30* and 125 *31* are 130

31 are packed against leakage by suitable packing 42 compressed by means of glands 43.

In order to assure that the reversing switch will be thrown to its neutral position when the electrode E is in its uppermost position, a safety control device 44 is provided in the motive fluid supply pipes 32 and 33. The safety control device includes 10 a pair of valves 45 (Fig. 7) which are adapted to exhaust the pipes 32 and 33 of any fluid under pressure which may have remained therein. The valves 45 are inclosed in a casing 46 and are of the poppet type 15 each adapted to slide in a cylindrical bore 47 of the casing 46 and seat as at 48 at the mouth of a chamber 49 into which the supply pipe 33 communicates. The pipe 33' leads out from the chamber 49 to the reversing switch. Likewise a corresponding pipe 32' leads to the reversing switch for effecting its operation in the reverse direction. The valve 45 is normally held onto its seat by means of a coil spring 50 pressing against 25 the head of the valve and removable from the casing 46 upon removal of a plug 51 threaded into an aperture 52 coaxial with the bore 47. If the valve 45 is lifted from its seat 48 any residual air under pressure 30 in the pipes 33 and 33' is adapted to flow into the bore 47 around the reduced neck 52 of the valve and thence to atmosphere through suitable ports 53 in the casing 46.

The valves are adapted to be unseated by 35 means of a finger 54 rigidly mounted on the shaft q (Fig. 1) in such a position that the finger 54 pressed against the valve 45 when the electrodes E are in their uppermost position or when the piston Z is in its lowermost position. Thus, if it is desired to break 40 the circuit by raising the electrodes E out of the liquid R, the reversing switch will be caused to break the circuit before the electrodes E are again submerged in the liquid 45 R.

Means is provided to prevent the reversing switch from being operated by swinging the lever v from one extreme position to the other until the rheostat has caught up with 50 the movement of the lever v. To this end there is provided a pair of plungers 55 and 56 adapted to project into the path of a plate 57 in the form of a sector of a circle (Fig. 1). The plungers 55 and 56 are adapted 55 to be actuated by motive fluid supplied from the chambers 37 and 38 respectively in precisely the same manner as the supply pipes 32 and 33 respectively. The base 58 supporting the valve casing 9 is provided 60 with a pair of transverse bores 60 in which the plungers 55 and 56 have a sliding fit. The communicating passages 61 connect the chambers 37 and 38 with bores 60 to supply fluid under pressure for depressing the plungers. Normally the plungers are held with-

drawn by suitable coil springs about the stems of the plungers 55 and 56 to permit the arm 4 to move in either direction as shown in Fig. 3. Having moved the arm 4 in one direction, however, as for instance shown in Fig. 1, the plunger 56 will be depressed by motive fluid supplied from the chamber 38 past the valve 31 to cause the stem of the plunger 56 to project into the path of the plate 57. Consequently, the arm 4 cannot be moved backwardly in the opposite direction beyond the center until the plunger 56 has been withdrawn, which occurs upon release of the air pressure behind that plunger by means of the valves 45. The operation of the plunger 55 to prevent the movement of the arm 4 is similar in all respects to the operation of the plunger 56.

The operation of the mechanism is as follows:

Starting with the circuit open at which position the lever v is vertical, the lever may be moved to the left (Fig. 1) causing the arm 4 to move toward the right and depressing the lever 7 by means of the link 8. This causes the link 20 to rotate the cam 17 to unseat the valve 14 permitting motive fluid to flow from the chamber 10 in the valve casing 9 (Fig. 2) into the pipe u leading to the lower part of the cylinder b. The piston Z is thereupon raised lifting the bell crank p and r mounted on the shaft q and raising the pivot 6 on the end of the arm 5. This raises the free end of the floating lever 7 and likewise pulls the link 20 upwardly causing the cam to resume a neutral position and permitting the valve 14 to close, shutting off the supply of motive fluid to the cylinder b. The swinging of the bell crank p and r raises the lever W to depress the electrodes e into the liquid. The depth of immersion of the electrodes e will depend upon the extent to which the control lever v is moved.

Simultaneously, the cam 34 is revolved depressing the plunger of the valve 31 and permitting motive fluid to flow into the pipe 33 to operate the reversing switch which closes the main circuit of which the rheostat herein described provides resistance. The lever v may be moved instantly to any position to the left of the vertical but is stopped from being moved beyond that position which would operate the valve 30 by the cam 34, by means of the stop plunger 56 which is depressed by motive fluid entering the passage 61 into the bore 60 and pressing the plunger 56 outwardly. Movement of the lever v to the right of the center is only possible after the electrodes E have been raised out of the fluid R to break the electrical circuit. In this position the finger 54 depresses both of the valves 45 permitting any residual motive fluid to escape from the pipes 33 and from the bore 60. The plunger-

ers 55 and 56 are thereupon released and movement of the lever *v* to the right is permitted.

On approaching the central neutral position of the lever *v* from any position, the arm 4 raises the link 20 which causes the cam 16 to depress the upper valve 13. The return of the cam 17 to its normal position is effected by the admission of motive fluid 10 from the chamber 10 past the valve 13 into the pipe 21 communicating with the pipe *t* to admit motive fluid above the piston *Z* pulling downwardly on the connecting rod *k* to raise the electrodes *E*.

15 The advantages of the apparatus will be apparent. It is impossible to reverse the reversing switch until the circuit is broken at the rheostat. Furthermore any desired gradation of resistance by simple movement 20 of the control lever remote from the rheostat itself may be made.

I claim:

1. A pneumatically controlled rheostat comprising a tank containing liquid and 25 electrodes adapted to be immersed in said liquid, a hand operated lever having positions corresponding to definite depths of immersion of said electrodes in said liquid, a cylinder and fluid actuated piston adapted 30 to raise and lower said electrodes in said liquid, and valves adapted to be actuated by said hand operated lever and restored to inoperative position by said piston, to control the raising and lowering of said piston 35 in said cylinder for setting said electrodes at the position corresponding to the position of said hand operated lever.

2. A pneumatically controlled rheostat comprising a tank, containing liquid and 40 electrodes adapted to be immersed in said liquid, a cylinder and fluid actuated piston adapted to raise and lower said electrodes in said liquid, a hand operated lever having 45 positions corresponding to definite depths of immersion of said electrodes, valves for controlling the flow of motive fluid to said cylinder, and a cam for actuating said valves, operable by said hand operated lever and restored by the motion of said piston.

5. A pneumatically controlled rheostat comprising a tank containing liquid, electrodes adapted to be immersed in said liquid, a cylinder and pneumatically operated piston for raising and lowering said electrodes 55 in said liquid, valves for controlling motive fluid for said piston, a cam for actuating said valves, a hand operated lever adapted to operate said cam and having positions corresponding to definite depths of immersion 60 of said electrodes in said liquid, and means controlled by said piston to restore said cam to inoperative position upon immersion of said electrodes to a depth corresponding with the position of said hand operated lever.

6. A pneumatically controlled rheostat

comprising a tank containing liquid and electrodes adapted to be immersed in said liquid, a cylinder and fluid actuated piston to raise and lower said electrodes in said liquid, valves for controlling the supply of motive fluid to said piston, a hand operated lever having a central neutral position and adapted to swing both ways to control said piston, a cam controlling said valves operable by said hand actuated lever and restored to its normal inoperative position by said piston, and electrical switch controlling valves selectively operable by said hand operated lever.

5. A pneumatically controlled rheostat 80 comprising a tank containing liquid and electrodes adapted to be immersed in said liquid, a cylinder and fluid actuated piston to raise and lower said electrodes in said liquid, valves for controlling the supply of motive 85 fluid to said piston, a hand operated lever having a central neutral position and adapted to swing both ways to control said piston, a cam controlling said valves operable by said actuated lever and restored to normal inoperative position by said piston, a pair of electrical switch controlling valves, and a cam operable by said hand operated lever to selectively operate said switch controlling 90 valves.

6. A pneumatically controlled rheostat comprising a tank containing liquid and electrodes adapted to be immersed in said liquid, a cylinder and fluid actuated piston to raise and lower said electrodes in said liquid, valves for controlling the supply of motive fluid to said piston, a hand operated lever having a central neutral position and adapted to swing both ways to control said piston, a cam controlling said valves operable by said hand actuated lever and restored to normal inoperative position by said piston, electrical switch controlling valves 100 selectively operable by said hand operated lever, and safety stop means to limit the movement of said hand operated lever, until said electrodes have been removed from said liquid.

7. A pneumatically controlled rheostat 115 comprising a tank containing liquid and electrodes adapted to be immersed in said liquid, a cylinder and fluid actuated piston to raise and lower said electrodes in said liquid, valves for controlling the supply of motive fluid to said piston, a hand operated lever having a central position and adapted to swing both ways to control said piston, a cam controlling said valves operable by said hand actuated lever and adapted to be restored to normal inoperative position by said piston, switch controlling valves selectively operable by said hand operated lever, safety stop means including a pair of plungers controlled by said switch controlling valves to 120 limit the movement of said hand operated 125 lever.

8. A pneumatically controlled rheostat 130 comprising a tank containing liquid and electrodes adapted to be immersed in said liquid, a cylinder and fluid actuated piston to raise and lower said electrodes in said liquid, valves for controlling the supply of motive fluid to said piston, a hand operated lever having a central position and adapted to swing both ways to control said piston, a cam controlling said valves operable by said hand actuated lever and adapted to be restored to normal inoperative position by said piston, switch controlling valves selectively operable by said hand operated lever, safety stop means including a pair of plungers controlled by said switch controlling valves to limit the movement of said hand operated lever.

lever until the removal of said electrodes from said liquid.

8. A pneumatically controlled rheostat comprising a tank containing liquid and electrodes adapted to be immersed in said liquid, a cylinder and fluid actuated piston to raise and lower said electrodes in said liquid, valves for controlling the supply of motive fluid to said piston, a hand operated lever having a central position and adapted to swing both ways to control said piston, a cam controlling said valves, operable by said hand operated lever and adapted to be restored to normal inoperative position by said piston, electrical switch controlling valves selectively operable by said hand operated lever, safety stop means to limit the movement of said hand operated lever until said electrodes have been removed from said liquid, and means to restore said safety stop means.

9. A pneumatically controlled rheostat

comprising a tank containing liquid and electrodes adapted to be immersed in said liquid, a cylinder and fluid actuated piston to raise and lower said electrodes in said liquid, valves for controlling the supply of motive fluid to said piston, a hand operated lever having a central position and adapted to swing both ways to control said piston, a cam controlling said valves, operable by said hand operated lever and adapted to be restored to normal inoperative position by said piston, electrical switch controlling valves selectively operable by said hand operated lever, safety stop means to limit the movement of said hand operated lever until said electrodes have been removed from said liquid and means controlled by said piston to restore said safety stop means.

In testimony whereof I have signed this specification.

HARRY V. HAIGHT.
